OIL DISTILLATE COOLER OR CONDENSER

John Samuel Wallis, New York, N. Y.

Application October 25, 1930. Serial No. 491,183

7 Claims. (Cl. 257—196)

My invention relates to coolers or condensers for cooling oil, that is hydrocarbon fluid, in oil distillation processes and the like.

Oil products leaving a fractionating tower or other oil treatment apparatus, pass through condensers or coolers or both. Since condensers are coolers, such devices will in general herein be termed coolers.

So far as I am aware, previously known commercial coolers consist of pipe coils submerged in a water tank. There are two objections to this known type of cooler; first, as respects space required; and, second, as respects heat transfer. The coils usually consist of vertically disposed rows of horizontal tube portions connected alternately at the ends by bends. The horizontal portions of these tubes are arranged about a foot apart. In a cooler of this known type, furthermore, the inside surface, which is contacted by oil, is less area than the outside surface, which is contacted by water. The specific heat of water is approximately twice that of oil, and the rate of heat transfer between metal and water is greater by several times than the rate of heat transfer between metal and oil. The heat transfer between the oil and the metal wall is consequently the limiting factor.

I propose to overcome the above disadvantages and to provide an improved cooler by replacing the tubes with castings. These castings have, preferably, smooth outside vertical walls. Internally the castings contain ribs which serve two purposes. The ribs are arranged to form a plurality of horizontal passages alternately connected at opposite ends of the castings. The ribs further appreciably increase the inside or oil contact surfaces relative to the external or water contact surfaces. Various forms of ribs may be used, but each casting is preferably so designed that the oil contact surface and the water contact surface are in inverse proportion, or at least substantially inverse proportion, to the specific heat of the respective fluids and preferably in inverse proportions to the rates of heat transfer between the respective fluids and the casting. Since the ribs are not quite as efficient as the side walls for the transmission of heat, I preferably provide an excess of internal surface above the ratio set forth. The vertical walls of the sides of the castings determine passages for the water between them. Since a greater length of path of flow, by several times, can be included in a given vertical height of casting than in a pipe type cooler, a smaller number of vertically disposed members can be employed, and consequently the size of the water

tank can be materially reduced. The reduction of the water tank provides greater velocity in the water tank between the castings and in contact with the side walls thereof, which increase in velocity is an aid to heat transfer and helps to improve the efficiency. I find that with the present invention the size of water tank for a given capacity can be cut substantially in half. Furthermore, since a smaller member of vertically disposed members can be employed, the oil velocity will be increased as compared with the previously known coolers and thus the heat transfer from the oil is also improved due to its velocity.

My invention is illustrated on the accompanying drawings, forming a part of this specification and on which:

Fig. 1 is an elevational cross-sectional view of one embodiment of the invention, taken on the line 1—1 of Fig. 2;

Fig. 2 is a transverse cross section taken on the line 2—2 of Fig. 1; and

Figs. 3 through 6 show different kinds of ribs for use in the casting of Figs. 1 and 2.

My improved cooler includes a water tank 10 having an inlet 11 and an outlet 12. Within the water tank is a plurality of vertically disposed oil contacting groups of cooling sections 14. Each group, in the embodiment shown, includes two castings disposed one above the other. Each casting has side walls 16 which are parallel and vertically disposed, a top wall 17, a bottom wall 18 and end walls 19. The end walls 19 are parallel and vertically disposed. The top and bottom walls 17 and 18 are parallel and horizontally disposed. At the top of each casting is an inlet 20 and at the bottom of each casting is an outlet 21. Spacing members 22 are cast integral with the castings.

Each casting is an integral casting, thus eliminating substantially all connections. Horizontal webs 24 extend between the side walls 16 and are of less length than the internal length of the casting. Alternate webs extend from opposite end walls to substantially the other end wall respectively. Each web terminates short of one end wall by an amount substantially equal to the distance between the webs. The webs thus form parallel horizontal passages which are connected in series alternately at opposite ends of the castings.

In the embodiment shown, four groups of castings of two castings each, are arranged vertically in the water tank 10. The upper connections of the upper castings are connected to a common inlet header 26, to which the oil is supplied. The lower ends of the lower casting are connected to

a common outlet header 27, through which the oil is conducted to storage or other place depending upon the process. I-beams 28 and saddles 29 or other supporting means may be provided to

5 support the castings. The oil flows in parallel downwardly through the castings, the castings being connected in series as shown in the drawings.

It will be seen that the external water-cooled surface of each casting is less than the internal oil contact surface due to the provision of the webs 24. As shown in Fig. 2, the webs 24 are slightly wider than the vertical distance between the webs. The internal surface has an area which is somewhat greater than twice the outside surface. This, as above stated, is done to compensate for the difference in specific heat and rate of heat transfer between oil and water. Tests have shown that webs do not give 100% heat transmitting efficiency, but webs arranged as shown in the drawing should give approximately 80% efficiency for the flows encountered in normal use for oil cooling. This factor should therefore be taken into account in increasing the internal surface above that which corresponds to the inverse ratio of 20 specific heats and heat transfer rates of the respective fluids.

Holes and plugs indicated at 30 are provided opposite each web at the point where it is spaced from an end wall. Each hole affords access to two 30 horizontal passages, thus facilitating cleaning with a minimum number of plugs. The plug holes are useful in casting the section.

By casting the sections integral, I provide a minimum of bolted joints, there being bolted joints 35 only where the castings are connected to the manifolds or headers and where the castings are connected to each other in such instances as a plurality of castings being used in each section. The use of a casting permits the horizontal oil 40 passages to be immediately adjacent each other and thus provide many more passages per unit height than with the old type of oil cooler. It is impossible to have the horizontal portions of a pipe cooler adjacent to each other on account 45 of the end bends or loops. My cooler provides this advantage, while at the same time giving the advantage of a proper heat transfer in accordance with the characteristics of the liquids. Since there are so many more horizontal passages, 50 the water tank can be reduced relative to the size required for a pipe cooler, and consequently the velocity of the water flowing upwardly and alongside the castings is greater than the rate of flow of water in a pipe cooler. Dead spaces between 55 horizontal pipe portions are eliminated, the castings acting as baffles to give positive flow.

Heat transfer increases with increased velocity, and therefore my cooler is improved in efficiency due to the faster flow of water caused by the 60 decrease of tank size, in turn caused by the use of castings.

The webs may be of various forms. Fig. 3 shows horizontal webs wherein the webs are substantially as wide as the passages between the webs. 65 In this arrangement the internal surface is approximately twice the external surface. Fig. 4 shows webs of angular form, the internal surface extending obliquely to the side walls. This gives a greater amount of internal surface for a given width of casting.

Fig. 5 shows different forms of webs. To increase the internal surface, I provide fins 16'. It will be obvious that these fins may be employed in the other forms of construction shown. 70 In cases where internal parallel surfaces are used,

I prefer to have the bottom surface smooth and the other surfaces of irregular form. The reason for this is to prevent deposits on the bottom surface.

Fig. 6 shows still another form of web in which the web is thinner at the center than at the side walls. 75

It will be understood that the invention is not limited to the precise structure described and illustrated. For example, the casting need not necessarily be arranged vertically as shown. 80

What I claim is:

1. An integral casting for an oil cooler comprising parallel side walls, parallel end walls, parallel top and bottom walls, and internal webs parallel to the top and bottom walls and extending alternately from opposite end walls to substantially the other end wall respectively and providing a plurality of parallel passages for flow of oil connected in series, said passages having an internal surface of greater area than external surface and said webs being thicker adjacent the side walls than at more central points. 90

2. A water cooled oil cooler comprising a water tank having an inlet and an outlet, a plurality of parallel vertically disposed oil-conducting cooling sections in said water tank, each section consisting of a unitary casting having parallel side walls and internal webs, said webs extending alternately from opposite end walls of the casting to substantially the other end wall respectively and providing a plurality of parallel horizontal passages for flow of oil connected in series, said webs providing an internal oil contact surface greater than the external water contact surface, said webs being thicker adjacent the side walls than at more central points, and means comprising inlet and outlet headers for connecting the sections in parallel. 100

3. A water cooled oil cooler comprising a water tank having an inlet and an outlet, a plurality of parallel vertically disposed oil-conducting cooling sections in said water tank, each section consisting of a unitary casting having parallel side walls and internal webs, said webs extending alternately from opposite end walls of the casting to substantially the other end wall respectively and providing a plurality of parallel horizontal passages for flow of oil connected in series, said webs providing an internal oil contact surface greater than the external water contact surface, said webs having surfaces extending obliquely to the side walls, and means comprising inlet and outlet headers for connecting the sections in parallel. 110

4. A water cooled oil cooler comprising a water tank having an inlet and an outlet, a plurality of parallel vertically disposed oil conducting cooling sections in said water tank, each section consisting of a unitary casting having parallel side walls and internal webs, said webs extending alternately from opposite end walls of the casting to substantially the other end wall respectively and providing a plurality of parallel horizontal passages for flow of oil connected in series, said webs providing an internal oil contact surface greater than the external water contact surface, said passages for flow of oil having smooth bottom surfaces and one or more other irregularly surfaced walls, and means comprising inlet and outlet headers for connecting the sections in parallel. 120

5. An integral casting for an oil cooler comprising parallel side walls, parallel end walls, parallel top and bottom walls, and internal webs

parallel to the top and bottom walls and extending alternately from opposite end walls to substantially the other end wall respectively and providing a plurality of parallel passages for flow 5 of oil connected in series, said passages having an internal surface of greater area than external surface and said webs having surfaces extending obliquely to the side walls.

6. An integral casting for an oil cooler comprising parallel side walls, parallel end walls, parallel top and bottom walls, and internal webs parallel to the top and bottom walls and extending alternately from opposite end walls to substantially the other end wall respectively and 15 providing a plurality of parallel passages for flow of oil connected in series, said passages having smooth bottom surfaces and one or more other irregularly surfaced walls.

7. An oil cooler comprising in combination a casing adapted to receive a cooling medium, a plurality of castings disposed within said casing adapted to be surrounded by said cooling medium, said castings having internally extended surfaces having a greater area than the external surfaces thereof, a part of said internally extended surfaces arranged to constrain the flow of the liquid within the castings in predetermined paths, another part of said internally extended surfaces adapted to provide an increased heat exchange surface, said last named surfaces being disposed to avoid resistance to the flow of a liquid thereover, inlet openings for said castings, outlet openings for said castings and respective manifolds communicating with said inlet and outlet openings.
